(57) **CLAIM**

The ornamental design for a slide sandal as shown and described.

DESCRIPTION

FIG. 1 is an isometric view of a slide sandal showing my new design;

FIG. 2 is another isometric view of the slide sandal of FIG. 1;

FIG. 3 is a top view of the slide sandal of FIG. 1;

FIG. 4 is a bottom view of the slide sandal of FIG. 1;

FIG. 5 is a front view of the slide sandal of FIG. 1;

FIG. 6 is a rear view of the slide sandal of FIG. 1;

FIG. 7 is a first side view of the slide sandal of FIG. 1;

FIG. 8 is a second side view of the slide sandal of FIG. 1;

FIG. 9 is an isometric view of another slide sandal showing my new design;

FIG. 10 is another isometric view of the slide sandal of FIG. 9;

FIG. 11 is a top view of the slide sandal of FIG. 9;

FIG. 12 is a bottom view of the slide sandal of FIG. 9;

FIG. 13 is a front view of the slide sandal of FIG. 9;

FIG. 14 is a rear view of the slide sandal of FIG. 9;

FIG. 15 is a first side view of the slide sandal of FIG. 9; and,

FIG. 16 is a second side view of the slide sandal of FIG. 9.

The broken lines in the drawings depict portions of the slide sandal that form no part of the claimed design.
